UNITED STATES PATENT OFFICE.

WILLIAM T. SMITH, OF PHILADELPHIA, PENNSYLVANIA.

DESIGN FOR A WOVEN FABRIC.

SPECIFICATION forming part of Design No. 23,017, dated January 23, 1894.

Application filed December 22, 1893. Serial No. 494,469. Term of patent 3½ years.

To all whom it may concern:

Be it known that I, WILLIAM T. SMITH, a citizen of the United States, residing at Philadelphia, in the county of Philadelphia, and State of Pennsylvania, have invented and produced a new and original Design for a Woven Fabric, of which the following is a specification, reference being had to the accompanying drawing.

The leading feature of my design is represented and shown in the accompanying draw-

ing, which is sufficient to enable others skilled in the arts to make and use my invention.

Having as above fully described my invention, what I claim as new, and desire to secure by Letters Patent, is—

The design for a woven fabric, as shown in the accompanying drawing.

W. T. SMITH.
